UNITED STATES PATENT OFFICE

112,456

DESIGN FOR A DESK PENHOLDER

Herman Bohme, Oakland, Calif.

Application March 19, 1938, Serial No. 75,978

Term of patent 3½ years

To all whom it may concern:

Be it known that I, Herman Bohme, a citizen of the United States and a resident of the city of Oakland, county of Alameda, State of California, have invented a new, original, and ornamental Design for a Desk Penholder, of which the following is a specification, reference being had to the accompanying drawing, forming part thereof.

The figure is a perspective view of the desk penholder showing my new design.

I claim:

The ornamental design for a desk penholder, substantially as shown.

HERMAN BOHME.
